(No Model.)

N. B. THWEATT.

FIRE BACK.

No. 269,551.

Patented Dec. 26, 1882.

N. PETERS, Photo-Lithographer, Washington, D. C.

UNITED STATES PATENT OFFICE.

NICHOLAS B. THWEATT, OF HICKORY PLAINS, ARKANSAS.

FIRE-BACK.

SPECIFICATION forming part of Letters Patent No. 269,551, dated December 26, 1882.

Application filed October 7, 1882. (No model.)

To all whom it may concern:

Be it known that I, NICHOLAS B. THWEATT, of Hickory Plains, in the county of Prairie and State of Arkansas, have invented certain new and useful Improvements in Fire-Backs; and I do hereby declare that the following is a full, clear, and exact description of the invention, which will enable others skilled in the art to which it appertains to make and use the same, reference being had to the accompanying drawings, which form a part of this specification.

Figure 1 is a perspective view of my improved fire-back. Fig. 2 is a horizontal sectional view. Fig. 3 is a perspective view, showing the fire-back extended; and Fig. 4 is a rear view.

Corresponding parts in the several figures are denoted by like letters of reference.

This invention relates to that class of fire-backs or linings for open fire-places which are adjustable, so that they may be made to fit in fire-places of various sizes; and it consists in certain improvements in the construction of the same, which will be hereinafter fully described, and particularly pointed out in the claim.

A A in the drawings represent a pair of angle-plates.

B is the back plate, which is provided with rearward-projecting bolts C, fitting in slots D in the rear leaves, E, of the angle-plates A.

F F are the side plates, which are provided with bolts G, fitting in horizontal slots H in the forward leaves, I, of the angle-plates. The several bolts C and G are provided with nuts J, which, when tightened, serve to secure the plates B and F in the desired position in relation to the angle-plates.

The side plates, F, are provided at their front ends with outwardly-projecting flanges K. The outer or rear sides of the side plates, F, and back plate, B, are provided with vertical ribs or corrugations L to receive lugs M, projecting from the ends of the angle-plates A. When the side plates and back plate have been adjusted in the proper position in relation to the angle-plates, so as to adjust the fire-back to any desired size, the lugs M, by entering the grooves between the ribs or corrugations L, serve, when the nuts J are tightened upon their respective bolts, to retain the parts securely in position and prevent the device from expanding or collapsing.

The operation of my invention will be readily understood. By simply loosening the nuts the parts may be readily adjusted to any desired position, thus fitting my improved fire-back to a fire-place of any size. The plates A, B, and F, constituting my invention, may be made of cast-iron or of any other suitable material.

Having thus described my invention, I claim and desire to secure by Letters Patent of the United States—

The combination, with the angle-plates A, having slots D H and lugs M, of the adjustable back plate, B, and side plates, F, having vertical ribs or corrugations L, and nuts J and bolts C G, as and for the purpose set forth.

In testimony that I claim the foregoing [as my own I have hereto affixed my signature in presence of two witnesses.

NICHOLAS B. THWEATT.
